UNITED STATES PATENT OFFICE.

JOHN H. BENTLEY AND WILLIAM GREGORY, OF PATERSON, NEW JERSEY.

COP-WINDING MACHINE.

SPECIFICATION forming part of Letters Patent No. 772,603, dated October 18, 1904.

Application filed January 19, 1903. Serial No. 139,576. (No model.)

To all whom it may concern:

Be it known that we, JOHN H. BENTLEY and WILLIAM GREGORY, citizens of the United States, residing at Paterson, in the county of Passaic and State of New Jersey, have invented certain new and useful Improvements in Cop-Winding Machines, of which the following is a specification, reference being had therein to the accompanying drawings.

10 Our invention relates to improvements in cop-winding mechanism; and it consists, first, in a loosely-mounted cop-forming cup through which the spindle is permitted to rise with the formation of the cop; second, in a compound clutch device for driving the spindle and stopping it when disconnected, and, finally, of a mechanism for starting the spindle in its upward movement at the beginning of the formation of the cop. While our machine applies to cop-winding generally, it is especially designed for winding a hollow cylindrical cop with a rounded or somewhat-conical nose and base, from which in use the thread can be drawn either from the interior or exterior, 25 but preferably from the interior.

The object of our invention is to provide a machine that will produce a tubeless cop adapted for use in shuttles for weaving purposes and which will so wind the cop as to permit 30 the thread to be delivered from either the interior or exterior of the cop with evenness and regularity when it is carried through the shed by the shuttle in the process of weaving.

The further object of our invention is to provide such a machine with a loosely-mounted cup or thimble to surround that portion of the spindle whereon the cop is formed and having a hollow conical-shaped interior.

A further object of our invention is to provide in such a machine means to start the spindle in its vertical movement at the time that the cop is beginning to be formed; and a further object of our invention is to provide the clutching mechanism with an adjustable friction device that will cause the spindle to revolve gradually for a period before the main clutching devices are engaged to rotate the spindle at its usual speed; and a still further object of our invention is to provide automatic means

for disengaging the clutch devices to stop the 50 spindle automatically upon the breaking of a thread and for withdrawing the spindle from the cop when it is finished.

In the accompanying drawings like characters of reference indicate like parts. 55

Figure 1 is an end view of a portion of a machine embodying our improvements. Fig. 2 is a side elevation of same, showing our compound clutch device in section. Fig. 3 is a plan view of a portion of a machine, showing 60 a method of imparting a vertical movement to the spindle from the main shaft. Fig. 4 is a section through our cop-forming cup, showing the method of loosely mounting the same in the upper table of the machine. Fig. 5 65 shows detail views of the automatic spindle-elevating device, both in section and in elevation, the section being on the line $z z$, the device being out of operative engagement. Fig. 6 shows detail views the same as Fig. 5, with 70 the exception that the swinging pawl and ratchet of the spindle-elevating device are in operative engagement. Fig. 7 is a view similar to Fig. 1, but enlarged, and showing a mechanism for driving the spindles; and Fig. 75 8 is a plan view of one set of four spindles, showing the mechanism for driving the same.

The operating mechanism connecting the shaft 1 with the gearing 31 consists of a miter-gear a , which is secured to said shaft 1 and meshes with a miter-gear b , which is secured to the spur-gear c , and the spur-gear meshes with the gearing 31. The shaft c is mounted in the support or bearing d , and to the shaft c is secured the spur-gear c and the miter-gear b . The bearing d is secured to the frame 80 26. The spur-gears 31 are secured to the spindles 11, which are operated from the main shaft 1 through the above-described operative connections. 85

Power is communicated to the main driving-shaft 1 of the machine by belt or pulley or in any other suitable manner. A worm 2 is secured to the shaft 1 and engages a worm-gear 3, secured on shaft 4, which is mounted 95 at right angles to the main shaft. On each end of the shaft 4 are secured worms 5, which engage and turn worm-gears 6, secured to the

shafts 77, which are mounted parallel to each other on either side of the machine and at right angles to the shaft 4.

On the shafts 77 are secured ratchet-wheels 58, one for each spindle on the machine, and these ratchets 8, turning with the shafts 7, are adapted to engage the swinging pawls 13 when said pawls are swung in the direction of the ratchet by the arm 10, which is secured to the connecting-rod 9 upon the upward movement of the said rod.

The swinging pawl 13 is suitably mounted in the fixed bracket 12, secured to the spindle 11. As illustrated in Figs. 5 and 6, the turning of the ratchet in engagement with the swinging pawl 13 causes the spindle to rise until the pawl 13 has been carried to a point beyond the engagement of the ratchet. This elevating of the spindles by means of the ratchet 8 and swinging pawl 13 is gradual and continuous while it lasts and takes place at the beginning of the formation of the cop, as it will hereinafter more fully appear, and prevents the bunching of the thread, which is otherwise liable to occur, and by providing for the distribution of the thread on the rising spindle insures a good foundation for the commencement of the cop-building process.

The bracket 12, which is secured to the spindle 11 and in which the swinging pawl 13 is mounted, has a forked end passing on either side of the connecting-rod 9, and from the top of the bracket 12 passes a chain or cord 14, one end of which is secured to said bracket 12, and thence over a sheave or roller 15, which is secured to said connecting-rod 9, and a weight 16 is secured to the other end of said chain or cord. On the upper table 17 of the machine is secured a tilting block 19 on a base 18.

The tilting block is provided with a handle 19^a and the usual arm 20.

The tilting block 19 is pivotally secured to the stand 18, and the connecting-rod 9 is pivotally connected with the rear upper portion of the tilting block 19, as is indicated by 21. When the tilting block 19 is tipped back, as indicated to the right in Fig. 2, the connecting-rod 9 is lowered and our compound clutch device is disengaged, so that the spindle 11 is not rotated; but when the tilting block 19 is down and forward, as is indicated to the left in Fig. 2, the connecting-rod 9 is drawn up and the clutching devices become engaged, as shown in said figure, and the rising connecting-rod 9 causes the arm 10, secured thereto, to press the swinging pawl 13 toward the ratchet 8 to be engaged thereby, which engagement immediately causes the spindle 11 to rise gradually within the cop-forming cup 22.

The rod 9 is only raised, as shown to the left in Fig. 2, to engage the clutch mechanism preparatory for the operating of the machine, and is lowered, as shown to the right

in Fig. 2, when the cop is finished and the tilting block 19 is tipped back, disengaging the clutch mechanism and stopping the operation of the spindle.

Owing to the point of connection of the rod 9 and the tilting block 19 the pressure of the friction-cone 59 of the rising spindle 11 against the friction-cone 58 on the rod 9 causes the tilting block 19 to be tipped back, as shown on the right in upper portion of Fig. 2, and the weight 16 aids in the tipping of the tilting block and the drawing down of the rod 9.

The mere engagement of the friction-cone 59 with the friction-cone 58 is in itself sufficient to accomplish the tipping of the tilting block, and the weight 16 may or may not be used. Said cup 22 is provided with a vertical slot 8 in one side thereof and on two sides with a recess, into which recesses 24 the arms of the plate 23 are adapted to fit loosely. The opening in the plate 23 is the shape of a horse-shoe, and the plate itself is secured to the stand 18. The cup is capable of a slight motion or movement in any direction and is held in place in the plate 23 by the spindle 11, which passes therethrough.

It is not deemed necessary in this application to show how the cop is formed by the traverse of a vibrating distributing device which conveys the thread up and down through the said slot, as the thread is being wound upon the spindle 11.

The cup 22, as shown in Fig. 4, has an opening therethrough to receive the upper end of the spindle 11. The upper portion 55 of said opening is larger than the opening in the lower portion of the cup. The opening in the lower portion is cone-shaped, and the opening in the upper portion is bell-shaped, as shown in Fig. 4, and where the bell-shaped portion 55 meets the lower cone-shaped portion 56 an annular ridge 57 is formed, which is smaller in circumference than any other portion of the opening through the cup, but which allows to a certain extent for any vibration of the spindle. This movability of the cup aids in the formation of the cop and allows for a more perfect adjustability of the cup to the cop during the winding process, and the rounded conical-shaped shoulder 25 makes the movement of the cup 22 free. On the lower supporting-table 26 of our machine is secured the rail 27, which carries our auxiliary clutch and which is provided with the cylindrical sleeve 27^a. A sleeve 28, having an annular flange 29 at its lower end, is secured in the sleeve 27^a and through said inner sleeve 28 the spindle 11 passes and turns. Between the inner sleeve 28 and the outer sleeve 27^a is a loose sleeve 30, adapted to be rotated around the inner fixed sleeve 28 above the annular flange 29. Said intermediate sleeve 30 has secured to it a gear 31, which is driven from the main shaft 1. On the lower portion of the loose sleeve 30 and integral therewith is a hollow cylindrical por-

110
115
120
125
130

tion 32, having on its inner side two oppositely-located lugs 33, which forms a portion of our compound clutch.

The lower portion of our clutch consists of 5 the plate 34, having an extended hub with a central opening therethrough provided with a feather or key adapted to slide in a key-seat or longitudinal slot in the spindle which passes through the central opening in the plate 34, 10 as indicated at 36 in Fig. 2. On the upper surface of the plate 34 are two lugs or jaws 35, adapted to engage the corresponding lugs 33 in the upper clutch member. The spindle 11 projects below the bottom of the clutch 15 member 34 and through an opening in the arm 37, which is secured to the lower end of the connecting-rod 9, so that when the tilting block 19 is tripped and falls back, as is shown to the right in Fig. 2, the connecting- 20 rod 9 is lowered, the lower clutch member drops out of engagement with the upper clutch member and rests on a lever-arm 37, through which the spindle 11 passes. The reverse is the case when the tilting block is 25 down in working position, the jaws of the upper and lower clutch members are engaged, and the spindle being keyed to the lower clutch member is rotated.

While the lower clutch member is keyed in 30 the spindle, it is obvious that it is movable lengthwise of the spindle the length of the slot in which the key engages. We do not, however, rely solely upon the engaging lugs of the upper and lower clutch members for 35 the rotation of the spindles, as the sudden engagement of the lugs and the immediate imparting of great speed to the spindle causes too great a strain upon the mechanism and upon the threads. We therefore employ an 40 auxiliary clutch member to start the spindle in its rotary movement at the time the cop is beginning to be formed and for a short period before the lugs of the upper and lower clutch members are engaged, which will rotate the 45 spindle at a lower speed, and thus avoid the breaking of the thread. This auxiliary clutch member consists of the adjustable spring-band 38, which is secured to an annular shoulder on the clutch member 34 on pins which pass into 50 longitudinal openings 40 in the said bands, the ends of said band being adapted to be drawn together by the tightening and loosening device 39 to regulate the friction or grip of the band on and around the outer surface of the 55 hollow cylindrical portion 32 of the sleeve 30. Said spring-band extends a distance above the lugs 35 on the clutch member 34, and by virtue thereof the friction of the spring-band, with the sleeve 30, turns the lower clutch 60 member 34 until the lugs 33 and 35 become engaged, so that the formation of the cop has been well begun before the spindle is rotated at full speed.

We employ a hand-operated device which 65 is connected with the spindle for the purpose

of doffing the cop. By pressing on the hand-lever of the device the spindle is forced downwardly out of the cop when the cop is completed, and the thread first wound around the spindle at the commencement of the formation 70 of the cop is the delivery end of the thread when the cop is placed in the shuttle for weaving purposes. It is thus obvious that the thread is delivered from the interior of the cop. On the connecting-rod 9 is 75 secured a friction-cone 58, and on the spindle 11 is secured a friction-cone 59. When the cop is completely formed on the spindle 11 in the cup 22, the spindle 11 is elevated to such an extent that the friction-cone 80 59 engages the friction-cone 58 on the rod 9, and the lateral pressure thus produced trips the tilting block 19, thus lowering the rod 9 and the clutch-support connected to the lower 85 end thereof, disengaging the clutch, and stopping the rotation of the spindle 11. (See right-hand portion of Fig. 2 in the drawings.)

With this description of our invention, what we claim, and desire to secure by Letters Patent, is—

1. The combination with the frame and a rotating spindle, of a non-rotating, cop-forming cup loosely held in said frame, and provided with a trumpet-shaped mouth, and a cone-shaped opening connecting therewith 95 forming on the interior of the cup an annular ridge and a bearing having arms upon which said cup is loosely held to permit the cup to oscillate about said rotating spindle, substantially as set forth.

2. The combination with a spindle and the frame, of a cop-forming cup loosely supported by said frame in a manner to permit of oscillating movement thereof, provided with a trumpet-shaped mouth and a cone-shaped 105 opening connecting therewith, forming an interior annular ridge at the smallest portion of the opening through the cup, and means for continuously elevating the spindle through the opening in said cup while rotating, substantially as set forth.

3. The combination of the frame, a non-rotating but rocking cop-forming cup loosely mounted thereon, and a spindle passing through said cup and holding it against displacement, with the main driving-shaft, and operative connections between said shaft and spindle to impart to the latter a continuous vertical movement, substantially as set forth.

4. The combination with a spindle and a driving mechanism therefor, of a connecting-rod having an arm at its lower end provided with an opening through which the lower end of the spindle passes, a tilting block pivotally secured to the upper end of said rod, a roller also secured to said rod, a bracket secured to said spindle, a weight suspended by a cord which passes over said roller and is secured to said bracket, clutch connections for said spindle and friction-cones secured respectively as set forth.

tively one to said spindle and one to said connecting-rod, said cones coacting to disengage the clutch connections to trip said tilting block and stop the spindle, substantially as set forth.

5. In a cop-winding machine the frame and a spindle passing therethrough, a rail having a downwardly-extending cylindrical portion, a sleeve having an annular flange at its lower extremity secured in said cylindrical portion, 10 an intermediary sleeve, adapted to rotate around the same and rest upon said annular flange, provided with a downwardly-extending cylindrical portion having therein two oppositely-located lugs and a gear secured to 15 said intermediary sleeve, in combination with a lower clutch member having an extended hub loosely surrounding the lower portion of the spindle and two oppositely-located lugs upon its upper face, means for guiding said 20 hub, an auxiliary adjustable friction-clutch member on said lower clutch member extending above its said lugs to engage the cylindrical portion of said intermediary sleeve, a tilting block, a rod at one end pivotally connected to said block, and at its lower end 25 having an arm passing around the spindle and forming a support for the lower clutch member, and means for engaging and disengaging the clutch mechanism, substantially as set 30 forth.

6. In a cop-winding machine, a non-rotating cop-forming cup provided with a horizontal recess in each side thereof, a vertical slot in one side thereof, a trumpet-shaped 35 mouth and a cone-shaped opening communicating therewith and forming inside the cup at the point of communication an annular ridge or projection adapted to loosely surround a spindle, in combination with a plate 40 having projecting arms engaging the horizontal recesses in the cup, forming a loose support therefor and permitting it to oscillate, substantially as set forth.

7. The combination with the frame, of a 45 cup-supporting plate 23 provided with projecting arms, a non-rotating cop-forming cup provided with a vertical slot in one side thereof and having horizontal recesses in both sides thereof to engage the arms of the plate 23, a 50 trumpet-shaped mouth and a cone-shaped opening communicating therewith forming inside the cup at the point of communication an annular ridge or projection adapted to loosely surround a spindle and permit the cup 55 to oscillate and a spindle passing through said cup and adapted to hold said cup loosely in position in said supporting-plate and means for holding said supporting-plate in position, substantially as set forth.

60 8. The combination with the frame, of a main shaft, a shaft mounted at right angles to, and deriving motion from, said main shaft, a shaft mounted at right angles to, and deriving motion from, said last-mentioned shaft, 65 a ratchet secured to and rotating with the

last above-mentioned shaft, a spindle mounted in said frame and rotated by the main shaft, a fixed bracket, having a forked end, secured to said spindle, a swinging pawl mounted in said bracket, a vertically-movable 70 connecting-rod passing between the forked ends of said bracket, an arm projecting from said connecting-rod and adapted to throw the swinging pawl into engagement with said ratchet to gradually raise the spindle when it 75 begins to rotate, substantially as set forth.

9. The combination with a non-rotating cop-forming cup, provided with a vertical slot in one side thereof, a trumpet-shaped mouth and a cone-shaped opening communicating therewith and forming inside the cup at the point of communication an annular ridge or projection adapted to loosely surround a spindle and permit the cup to oscillate of the frame, 80 a main shaft, a shaft mounted at right angles to, and deriving motion from, said main shaft, a shaft mounted at right angles to, and deriving motion from, said last-mentioned shaft, a ratchet secured to and rotating with the last 85 above-mentioned shaft, a spindle mounted in 90 said frame and rotated from the main shaft, a fixed bracket, having a forked end, secured to said spindle, a swinging pawl mounted in said bracket, a vertically-movable connecting-rod passing between the forked ends of 95 said bracket, an arm projecting from said connecting-rod and adapted to throw the swinging pawl into engagement with said ratchet to gradually raise the spindle when it begins 100 to rotate, substantially as set forth.

10. The combination with the frame, a main shaft, a rotating spindle driven therefrom, and a loosely-held non-rotating cup carried by the frame and surrounding the upper end of said spindle, the opening through said cup forming a trumpet-shaped mouth at the top and a communicating cone-shaped passage at the bottom, of a bracket mounted on said spindle and provided with a forked end, a swinging pawl mounted in said bracket, a 105 shaft having a ratchet to engage said pawl secured thereto, and deriving its motion from the main shaft, a vertical connecting-rod passing between the forked ends of said bracket, a tilting block pivotally secured to 110 the frame, and its upper rear portion pivotally connected with the upper end of said connecting-rod, an arm projecting from the lower end of said connecting-rod and provided with an opening through which the 115 lower end of said spindle is adapted to pass, a lower clutch member keyed to the lower end of said spindle adapted to slide vertically thereon and be supported by the arm on the lower end of said connecting-rod, an upper 120 clutch member loosely mounted on said spindle deriving its motion from the main shaft and adapted to engage the lower clutch member when the latter is raised into operative connection with the former by said tilting 125 130

block thereby elevating the connecting-rod which supports the lower clutch member, an arm secured to said connecting-rod to throw said swinging pawl into engagement with 5 said ratchet thereby gradually raising the spindle when the connecting-rod is elevated and motion is communicated to the spindle from the main shaft, substantially as set forth.

11. The combination with the frame, a rotating spindle and a plate having projecting arms, of a non - rotating cop - forming cup 10 loosely supported by said arms in a manner to permit of an oscillating movement thereof, and means for continuously elevating the 15 spindle through the opening in said cup while rotating, substantially as set forth.

12. In a cop-winding machine, clutch member 34 and the auxiliary clutch member consisting of the adjustable spring-band 38, in 20 combination with, and secured to, the annular shoulder on the clutch member 34, pins which pass into longitudinal openings 40 in said band, the sleeve 30 and the adjusting device 39 to regulate the friction or grip of 25

said band on portion 32, of the sleeve 30, substantially as set forth.

13. The combination with the frame and a rotating spindle, of a non-rotating cop-forming cup loosely held on said frame, and a bearing upon which said cup is loosely held 3 to permit the cup to oscillate about said rotating spindle, substantially as set forth.

14. The combination with the frame and a non-rotating cop-forming cup, of a bearing upon which said cup is loosely held to permit the cup to oscillate, a spindle mounted on 35 said frame, and passing vertically through said cup, and operative means coacting to communicate to said spindle concurrently a rotary and a vertical movement, substantially 40 as set forth.

In testimony whereof we affix our signatures in presence of two witnesses.
